RADIATOR CAP WITH RELEASE VALVE
Tom B. Miller, Grand Blanc, and Harry W. Nimmo,
Davisson, Mich., assignors to General Motors Corpora-
tion, Detroit, Mich., a corporation of Delaware
Filed Apr. 18, 1961, Ser. No. 103,752
1 Claim. (Cl. 220—44)

This invention relates to closures or caps such as employed on automobile radiators.

The primary function of such a cap is to seal a radiator neck and thereby close an engine cooling system and such a system is customarily pressurized for increased cooling efficiency. Pressures have increased in such systems in recent years but if the pressure in a given cooling system increases beyond a predetermined value it is conventional to have the excess pressure automatically relieved through a vent by means of a relief valve built into the cap. Also, if the cooling system pressure falls too low, a vacuum operated valve in the cap admits air preventing collapse of any part of the system. A valve with such features is disclosed in the United States Patent 2,266,314, issued December 16, 1941, in the name of J. E. Eshbaugh.

In the event a given cooling system is pressurized, removal or opening of the cap causes a sudden release in pressure and a consequent sudden increase in boiling of the engine coolant. The result often occurs that a rush of boiling coolant issues from the filler neck with an accompanying danger to the person removing the cap.

An object of the present invention is to provide an improved radiator cap with a manually operated and safe pressure release in an arrangement having no protruding lever or plunger detracting from its structural compactness.

A feature of the present invention is a radiator cap with a rotary cam arrangement operative about the axis of the cap to effect safe venting of a system to which the cap may be applied.

This and other features of the invention will become apparent from the following description.

In the drawings:

FIGURE 1 is a sectional view of one form of a radiator cap in which the present invention is embodied and a conventional radiator neck to which the cap is applied, the cap being shown with its parts positioned to close the radiator;

FIGURE 2 is a view similar to that of FIGURE 1 but with the parts positioned for venting the radiator;

FIGURE 3 is a top or plan view of the cap shown in FIGURE 1; and

FIGURE 4 is an exploded and perspective view of cam arrangement parts utilized in the cap of FIGURES 1, 2 and 3.

In FIGURES 1 and 2 of the drawings a portion 10 is depicted as a header tank part of a conventional automobile radiator. The coolant level when the radiator is full is shown at 12. A conventional filler neck 14 is soldered as at 16 to the radiator portion 10 and bears a lower inner valve seat 18 defining an opening 20 into the radiator. The upper end of the neck 14 bears a conventional outturned flange 22 having diagonally opposed notches and cam surfaces for engaging inturned tangs 24 and 26 of cover means generally indicated at 28. The neck 14 has a conventional vent 25 located between the seat 18 and the flange 22. The cover means 28 includes a metallic cup 30 having a peripheral downturned flange 32 from which the tangs 24 and 26 are formed. The cup 30 is circular except for two oppositely disposed ears 34 and 36 (FIGURE 3) facilitating manual tightening or removal of the cap with respect to the neck. An intermediate portion 38 of the cup

2

30 is depressed nonrotatably to receive the tabs 40 and 42 of a cam member 44. The latter is apertured at 46 freely to receive a shaft 48. The margin of the cam member 44 is thickened or formed at diametrically opposed areas to form two upwardly directed cam surfaces 49 and 50. The inner margin of the cam member 44 is so formed on the underside as to receive a sealing washer 52 which forms a seal with the shaft 48 and is firmly held in position between the cover member 30 and the cam member 44. A spring sealing disk 54 is held on the underside of the metallic cup 30 by means of an outturned flange 56 formed on the cup 30 and also by coiled springs as will further appear.

A plastic handle 60 overlies the metallic cup 30 and bears two arcuate cam surfaces 62 and 64 formed with radii such that these surfaces are adapted to engage the cam surfaces 49 and 50 when the handle is rotated about the shaft 48. Legends may be placed on the plastic handle 60 and the cup 30 as indicated in FIGURE 3. The upper end of the shaft 48 is formed pivotally to retain the handle 60 on the cap. The lower end of the shaft 48 is provided with two shoulders 66 and 68. The shoulder 66 is utilized to retain a coil spring 70 in compression against the underside of the valve spring disk 54 thereby preventing rattling of the parts when positioned as shown in FIGURE 1—that is, when the shoulder 68 is in the clear. A deepened and lengthened portion 71 of the plastic handle facilitates operation.

Valve means is generally indicated at 72 as being retained on the underside of the cover means 28 and is held to the handle 60 and metallic cup 30 by means of the shoulder 68 on the shaft 48. The latter passes through an aperture 75 formed in an inverted cup 76 forming a part of the valve means. The shoulder 68 on the shaft 48 is adapted to be maintained in engagement with the inverted cup 76 by means of a coil spring 78 acting between the spring disk 54 and a shoulder 80 formed on the cup when the cap is removed from the neck 14. The valve means 72 also includes a vacuum relief valve arrangement 82 which constitutes two inverted cups 84 and 86. The cup 84 is fitted tightly within the cup 76 and the cup 86 is loosely held to and within the cup 84 by means of a spring loaded pin 90. An aperture 92 is formed in the cup 84 to permit admission of air to the radiator 10 when a vacuum in the latter exceeds a predetermined value as established by the loading of a spring 94 as will be understood. A sealing disk 96 is utilized between the two cups 84 and 86 to form a seal under ordinary operating pressure conditions. A flange 100 on the cup 84 serves to retain a main sealing washer 102 in position on an outturned flange 104 of the cup 76. The washer 102 is adapted to engage the seat 18 of the filler neck.

The operation of the radiator cap may be understood from the above but it may be stated that in operation the valve parts are positioned as shown in FIGURE 1, a seal being formed at seat 18 by the washer 102 effectively closing the radiator 10 at pressures the maximum of which is determined by the loading of the spring 78. If too low a pressure should occur in the radiator, the cup 86 will lower against the spring 92 and admit air by way of the vent line and the opening 92. If the pressure in the radiator 10 should exceed a predetermined maximum value, it will compress the spring 78 and vent the radiator by disengagement of the washer 102 with its seat 18.

In the event an operator desires to remove the cap from the radiator, he will first turn the plastic handle 60 to the "open" position causing the cam surfaces 49 and 50 at 62 and 64 to be effective in moving the valve means 72 from the seat 18 as shown in FIGURE 2. The cam means will first assume the loading of the spring 78 and then, through the shoulder 68, the loading

of the spring 78. The radiator will then be effectively vented by way of the vent 25 and sudden release of pressure will cause an outflow in such a way that it may be directed to the ground and away from the operator. When the boiling stops the cover means 28 together with the plastic handle 60 may be rotated together and with respect to the filler neck and be removed with complete safety. Prior to or when the cap is replaced on the filler neck, the handle 60 must obviously be returned to sealed position so that when the metallic cup 28 is turned and firmly locked on the neck, the sealing washer 102 will engage the seat 18 under the loading of the spring 78 as shown in FIGURE 1.

We claim:

A radiator cap comprising cover means for a radiator neck opening, valve means of smaller diameter than said cap adapted to fit within said radiator neck opening, a shaft having one end supporting said valve means and having its other end extending through said cover means, means providing diametrically opposed upwardly directed cam surfaces on said cover means, each of said surfaces converging substantially to an apex, a rotatable handle member overlying said cover means and being secured

to said other end of said shaft, means providing downwardly extending opposed arcuate cams on said handle member, said cams having substantially planar surfaces adapted to engage said cam surfaces on said cover means, said planar surfaces contacting said apexes to hold said valve means in an open position and said apexes being receivable between said cams when said valve means is moved to its closed position, first spring means interposed between said cover means and said valve means and urging said valve means away from said cover means, and second spring means interposed between said cover means and said one end of said shaft thereby said cam surfaces on said handle member are maintained in engagement with said cam surfaces on said cover means.
